UNITED STATES PATENT OFFICE.

EARL S. R. BICKEL AND PENN DE BARTHE, OF PHILADELPHIA, PENNSYLVANIA, ASSIGNORS, BY MESNE ASSIGNMENTS, TO NATIONAL SOCIETY DAUGHTERS OF THE AMERICAN COLONISTS, OF WASHINGTON, DISTRICT OF COLUMBIA, A CORPORA-TION.

DESIGN FOR A BADGE OR SIMILAR EMBLEM.

Application filed August 5, 1922. Serial No. 3,295. Term of patent 14 years.

To all whom it may concern:

Be it known that we, EARL S. R. BICKEL and PENN DE BARTHE, citizens of the United States, residing in the city of Philadelphia, county of Philadelphia and State of Pennsylvania, have invented a new, original, and ornamental Design for a Badge or Similar Emblem, of which the following is a specification, reference being had to the accompanying drawing, forming a part thereof.

The drawing shows a front view of the badge constituting our design, suspended from a piece of ribbon which is indicated in dotted lines.

We claim:

The ornamental design for a badge or similar emblem as shown.

In testimony whereof we have hereunto set our names this 4th day of Aug., 1922.

EARL S. R. BICKEL.
PENN DE BARTHE.
